UNITED STATES PATENT OFFICE.

JOHN M. WOLBRECHT, OF LOS ANGELES, CALIFORNIA.

PNEUMATIC-TIRED VEHICLE.

SPECIFICATION forming part of Letters Patent No. 657,845, dated September 11, 1900.

Application filed November 22, 1899. Serial No. 737,938. (No model.)

To all whom it may concern:

Be it known that I, JOHN M. WOLBRECHT, a citizen of the United States, residing at Los Angeles, in the county of Los Angeles and State of California, have invented certain new and useful Improvements in Pneumatic-Tired Vehicles; and I do hereby declare the following to be a full, clear, and exact description of the invention, such as will enable others skilled in the art to which it appertains to make and use the same.

This invention relates to new and useful improvements in velocipedes and other pneumatic-tired vehicles; and its objects, among other things, are to provide a combined frame and reservoir designed to hold compressed air, to provide said frame with a pump adapted to be operated by the vibratory motions of the saddle or seat of the velocipede or vehicle, and to provide means for utilizing the compressed air for inflating, signaling, &c.

To these ends the invention consists in the novel construction and combination of parts hereinafter more fully described and claimed, and illustrated in the accompanying drawings, showing the preferred form of my invention, and in which—

Figure 1 is a section through a portion of a bicycle-frame. Fig. 2 is a detail view of the pump. Fig. 3 is a detail view of a modification.

Referring to said figures by letters of reference, A is the frame, formed of suitable tubing, one or more sections of which communicate through air-tight passages with the central tube or brace B of the frame.

Within the tube B is secured a tubular saddle-post C of peculiar construction, which may be adjusted vertically in the usual manner and held in position by means of a clamp b. This post C is closed at its lower end by a valve C', adapted to prevent the escape of air therethrough from the tube B. The lower portion of the walls of the post are preferably thickened, as at C², and a washer or partition c rests upon the shoulders formed thereby. This washer c serves as a bearing for one end of a spring D, which is mounted upon a tube E, detachably secured at its upper end to a hollow L-shaped seat-bar F, which is slidably mounted within the post C. The spring D

bears against the lower end of the L-shaped bar and serves to retain the same normally removed from the washer c. The tube E projects through the washer c into the chamber 55 c', formed in the bottom of the post C, and is provided with a piston E', within which is a valve e, as shown.

The upper end of the post C is preferably threaded and engages with a nut, as G, which 60 can be adjusted vertically upon the post for the purpose hereinafter described.

A valve H is preferably placed within the frame at the base of the tube B and is so constructed as to be opened when a tube is secured thereto. One way to secure this result is to form the stem h of the valve of such length as to come into contact with the nipple of the tube when the latter is placed upon the valve, thereby being forced inward. At 70 any other suitable point in the frame, preferably at the forward end of the upper horizontal bar B' thereof, is secured another valve I, operated in any suitable manner, as by a rod I'.

A whistle J communicates with the valve I and is adapted to be sounded when valve I is opened.

From the foregoing description it will be seen that the jarring and the resulting vibration of the seat or saddle will cause the seat-bar to move vertically within the post C, the spring D serving to cushion the same, as is obvious. When the seat-bar and its piston are forced downward, the air within chamber 80 c' will be forced through valve C' into the tubes of the frame, and upon the rebound or upward movement of said seat-post air will be admitted thereto and will enter the chamber c' through valve e of the piston E'. This 85 air or a portion of it will then be forced into the tubes of the frame upon the next downward motion of the saddle.

By regulating the length of the stroke of piston E the pressure within the frame can 95 also be regulated, as is obvious. I therefore in order to keep the pressure below the danger-point preferably so locate the top of the post C as to limit the stroke of the seat-bar to the proper length; but the stroke may, if 100 desired, be regulated by means of the nut G, which is mounted upon the post C.

The air which is accumulated within the tubing of the frame can be utilized for filling the tires of the velocipede by attaching a suitable pipe or tube to the valve H and conducting the air directly to the tire. By opening the valve I the whistle J may be sounded, thus obviating the necessity of using bells, &c., as heretofore.

In the foregoing description I have shown a form of pump adapted to be operated by the vibration of the entire saddle; but I am aware that the same result can be secured by employing the spring of the seat of the saddle. Such a construction is shown in Fig. 3 of the drawings, which shows the piston rod or tube K projecting upward through the seat-post and contacting with the under surface of the saddle-seat. The length of the stroke of this piston can also be regulated in any suitable manner, as by means of a nut K', adjustably mounted thereon.

It will of course be understood that the joints between the tubing and the frame of the velocipede must be perfectly air-tight, and this result may be secured with any suitable means, preferably by brazing or forging the parts upon a small tube L, inserted in the joint.

While I have shown and described this device as applied to a velocipede, it is obvious that the same can be used in connection with any vibratory seat and is therefore adaptable to automobiles and rubber-tired vehicles of all descriptions, a suitable reservoir being substituted for the tubing of a velocipede.

In the foregoing description I have shown the preferred form of my invention; but I do not limit myself thereto, as I am aware that modifications may be made therein without departing from the spirit of my invention and the same yet remain intact and be protected.

Having thus fully described my invention,

what I claim, and desire to secure by Letters Patent, is—

1. In a vehicle of the character described, the combination of a hollow post applied to the hollow vehicle-frame and having a valved chamber at its lower end, a hollow sliding seat-bar telescoping said post and having connected to its lower end a diametrically-reduced tubular rod carrying a valved piston arranged in said valved chamber, and a spring-support for said seat-bar, substantially as set forth.

2. In a vehicle of the character described, a combined pump and saddle-post comprising a post having a chamber at the lower end thereof with a valved outlet therefrom, a seat-bar slidably mounted within the post above the chamber, a valved piston having a hollow rod connection with said seat-bar and arranged within said chamber, and a spring-support for said seat-bar arranged intermediate of said chamber and seat-bar, substantially as described.

3. In a device of the character described, the combination of a reservoir having a valved air-outlet, a combined saddle-support and pump comprising a vertically-adjustable post having a chamber in its lower end provided with a valved outlet, a hollow seat-bar arranged to slide in said hollow post, a valved piston arranged in said chamber and having a detachable rod connection with said seat-bar within said post, and means to effect the adjustment of the length of the stroke of said piston, substantially as set forth.

In testimony whereof I affix my signature in presence of two witnesses.

JOHN M. WOLBRECHT.
